SAFETY SWITCH FOR AUTOMOBILES

Filed July 12, 1934

FIG. I.

INVENTOR.
WILLIAM A. WIMMER.
BY *Victor J. Evans & Co.*
ATTORNEYS.

UNITED STATES PATENT OFFICE

2,056,877

SAFETY SWITCH FOR AUTOMOBILES

William A. Wimmer, Long Beach, Calif.

Application July 12, 1934, Serial No. 734,831

1 Claim. (Cl. 200—52)

This invention relates to improvements in switches and has particular reference to an automatic switch for closing the circuit to perform certain functions under certain conditions.

5 The principal object of the invention is to provide a mercury switch which when installed upon a motor vehicle will sound an alarm if the vehicle is moved.

A further object is to construct the device in 10 such a manner that if the vehicle is moved under its own power as for instance, by bridging the customary ignition switch then the vehicle will miss fire and cause such an interrupted action that the car will shortly break down or the person 15 removing the car would quickly abandon the same.

Another object is to produce a device wherein should the vehicle tip beyond a certain limit the engine will be stopped.

20 A still further object is to provide means whereby if the vehicle should entirely tip over, not only will the engine stop but the horn will also be sounded so as to call help.

Other objects and advantages will be apparent 25 during the course of the following description.

In the accompanying drawing forming a part of this specification and in which like numerals are employed to designate like parts throughout the same,

30 Fig. 1 is a cross sectional view of the preferred form of my device and showing a schematic wiring system, and

Fig. 2 is a fragmentary cross sectional view of a portion of a modified form of my device.

35 In the accompanying drawing wherein for the purpose of illustration is shown a preferred embodiment of my invention, the numeral 5 designates a casing having insulating end pieces 6 and 7 attached thereto in any convenient manner.

40 Gaskets are shown at 8 whereby the device is sealed and a vacuum valve 9 is attached to the chamber thus formed. Extending through the bottom of the chamber is an adjustment plug 11 which regulates the sensitivity of the device. Ex- 45 tending through the top of the chamber are terminals 12, 13 and 14. The casing 5 is grounded at 16. Attached to the terminal 14 is a rod 17 which attaches to a plate 18. Insulation 19 surrounds the rod 17 and insulates the rod from a plate 21, which is electrically connected by a rod 22 to the terminal 12. A plate 23, of sub-

50 stantially the inside diameter of the chamber, is attached to the rod 22 and held in proper position by a spacer 24. A contact 26 is attached 55 to the terminal 13 and is insulated from any elec-

trical connection with the terminals 12 and 14. At A I have shown a conventional distributor, at B a conventional coil, at C an ordinary ignition switch, at D a horn button, at E the horn, and at F the battery, the distributor ground being 5 shown at G.

In the modified form, the parts perform the same functions and are, therefore, given the same numbers and a prime added thereto so that the plate 18 prime corresponds to the plate 18 of the 10 preferred form. The screw 11 in the modified form when screwed into the body of mercury, will raise the level of the mercury and bring it closer to the plates 18 prime and 21 prime. The screw 11 in the preferred form has a cone- 15 shaped head, and, consequently, the mercury will be thrown upwardly along the head into contact with the plates 18 and 21. This form of head provides for a very sensitive adjustment, if desired. 20

The operation of my device is as follows:—

Assuming that the switch H is closed, current will flow from the ground through the switch thence through the wire 27 to the sensitivity set screw 11, to the mercury 28 in the chamber. 25 Now, if the car, upon which the device is mounted, is jarred, the mercury will establish a circuit between the screw 11 and the plate 18, thence the current will flow through the rod 17, terminal 14, wire 29, switch H, wire 31 to wire 32 to one side 30 of the horn E thence to one side of the wire 33, battery F and ground of the battery, which will cause the horn to sound and this sounding will take place each time when the circuit is completed between the mercury and plate 18. Should the 35 motor be running, then the mercury will also complete a circuit to the plate 21, thence through the rod 22 to terminal 12 and by wire 34 to the wire 36, thus shorting out the ignition every time the circuit is completed between the mercury and 40 plate 21. This will cause the misfiring of the engine so badly that it will be practically useless for transportation purposes. When the switch H is opened the car may be run normally, but in case of accident which may upset the normal 45 level of the car, current will flow from the permanent ground 16 on the device to the mercury, thence to the disc 21 thence by terminal 12 and wire 34 to the ignition system again short-circuiting the distributor system and stopping the 50 motor.

When the car is turned over on its side the mercury will complete a circuit from the permanent ground to the plate 23 thence to the terminal 12 again permanently stopping the engine. 55

Should the car be turned over upon its top then the mercury will complete the circuit between the plate 23 and the ground, and also the mercury will complete a circuit between the contact 26 and the ground. This will not only stop the motor but will also cause the sounding of the horn, thus drawing attention to the overturned car.

In the modified form shown in Fig. 2, the arrangement of parts is identical with the exception that a different form of disc is employed. The discs which perform the same function are given corresponding numbers.

It will thus be seen that I have produced a device which will prevent thieves from stealing the car by not only giving an audible warning, but by short-circuiting the motor spasmodically so as to produce a jerky action, and I have also provided a device which under normal running conditions will give an alarm should the car turn over and will also interrupt the engine should the car tip beyond a predetermined angle.

It is to be understood that the form of my invention herewith shown and described is to be taken as a preferred example of the same and that various changes relative to the material,

size, shape and arrangement of parts may be resorted to without departing from the spirit of the invention or the scope of the subjoined claim.

Having thus described my invention, I claim:— 5

In a device of the character described, a metallic casing having a circular horizontal cross section, insulated end pieces connected therewith to form a chamber, the bottom of the chamber thus formed having a semicircular vertical cross section, a fluid positioned in said chamber, means for adjusting the level of said fluid, a pair of curved plates insulated from each other and centrally positioned above the bottom of said chamber, a conductor electrically connected to each of said plates and extending to a point outside of said chamber, a second plate spaced from said first mentioned plates and connected to one of said conductors, and a contact mounted at the top of said chamber and electrically connected to a point outside of said chamber, whereby when said device is turned upon its side or top said plates will be engaged by said fluid to complete an electrical circuit for the purpose designated. 10 15 20 25
